SCREEN

Michael Redelli, Brooklyn, N. Y.

Application May 29, 1940, Serial No. 337,901

3 Claims. (Cl. 156—10)

This invention relates to house furnishings and decoration, and more particularly refers to improvements in door and window screens of the curtain type.

Such screens are generally used in doors or windows for the purpose of concealing from view the space behind the screen, while allowing free ventilation, and virtually unimpeded passage beyond the screen. In most cases it is also necessary for a screen to form part of a decorative scheme, harmonizing with or contrasting from the other furnishings, in a manner calculated to enhance the general effect of a room ensemble.

The primary object of this invention is to provide a screen of the curtain type, composed of a plurality of independent units of a novel and improved construction, easily put together in a variety of design and color combinations.

Another object is to provide, in a screen of the curtain type, a novel and improved unit composed of a plurality of elements articulately connected end to end in chain-like formation to form a flexible elongated structure, said elements being easily and interchangeably connectable to one another for the purpose of attaining any one of a large variety of design and color combinations.

A further object is to provide a novel type of elongated element having each end adapted to cooperate with the adjoining end of an adjoining element in articulately connecting said elements to each other and to other similar elements end to end, to form a flexible elongated structure adapted to serve as one of a plurality of adjoining units suspended from a bar, to together form a screen of the curtain type allowing free passage and free ventilation.

Other objects and advantages of the present invention will more fully appear as the description proceeds and will be set forth and claimed in the appended claims.

My invention is illustrated by way of example in the accompanying drawings, in which:

Fig. 1 is a view in elevation illustrating the general appearance of a screen embodying my invention;

Fig. 2 is a fragmentary longitudinal sectional view in an enlarged scale showing one of the ways of connecting adjoining elements of one of the units composing the screen;

Fig. 3 is a cross sectional view through line 3—3 of Fig. 2;

Fig. 4 is a fragmentary longitudinal sectional view of one of the ends of an element provided 55

with an end piece forming part of a substantially spherical joint;

Fig. 5 is a fragmentary longitudinal sectional view of one of the ends of a tubular element formed with longitudinally extending prongs adapted to form part of a substantially spherical joint similar to that illustrated in Fig. 4;

Fig. 6 is a longitudinal sectional view of the end piece shown in Fig. 4, before the prongs are bent to form the spherical joint member;

Fig. 7 is a fragmentary longitudinal sectional view of one of the ends of a tubular element, in which the prongs are shaped to form the female member of a substantially spherical joint;

Fig. 8 is a fragmentary view in elevation of an adjoining end of an adjoining element, in which the prongs are shaped to form the male member of the spherical joint connecting the two elements;

Fig. 9 is a view, partly sectioned, of an alternative form of articulated device for connecting adjoining elements end to end;

Fig. 10 is a fragmentary longitudinal section through the attaching end of the uppermost element of one of the units composing the screen, illustrating a form of suspension piece therefor;

Fig. 11 is a similar view illustrating an alternative arrangement for attaching the suspension piece to the element;

Fig. 12 is a fragmentary longitudinal section through a unit composed of tubular elements articulately connected to one another in an alternative manner;

Fig. 13 is a fragmentary front view of a screen unit illustrating still another alternative construction; and

Fig. 14 is a partly sectioned side view thereof.

A screen made according to my invention, comprises a plurality of adjoining chain-like units suspended from a curtain rod or other means of attaching them at their upper end, said chain units together forming an open work curtain which will freely give to allow passage of a person therethrough. The units are arranged in close formation, giving the illusion of a practically uninterrupted surface, effectively concealing the space beyond the screen, the large number of air spaces intervening between the units providing for free ventilation between the rooms separated by the screen.

In a screen embodying my invention the elements composing the chain-like units are preferably directly connected to one another, and can be easily assembled to form any desired design and color combination. The elements can be

made of metal or wood, or of some plastic material, in a variety of shapes, colors and lengths, and any one element can be removed and replaced independently of the others, without making it necessary to disassemble or loosen all the elements composing a given unit in order to do so.

A typical screen embodying my invention is shown in Fig. 1, where 10 designates a window equipped with the screen 11. The screen consists of a plurality of flexible chain-like units 12, suspended side by side from a curtain rod 13, each unit being formed by articulately connecting elongated elements 14 end to end to one another, for instance, by means of spherical joints 15 such as shown by way of example in Figs. 2 and 3.

The elements 14, 14' shown in said Figs. 2 and 3 are in the form of relatively short lengths of metallic tubing, cut and shaped at each end to form two diametrically opposite, spring-acting segmento-spherical jaws 16, 16', adapted to embrace a spherical ball 17. In assembling the elements end to end, the ball is forced between the jaws 16 of one of the elements 14, and then the jaws 16' of the other element 14' are forced over the ball between jaws 16, thus completing an articulated or spherical connection between the two elements, which connection should be sufficiently loose to permit of the elements hanging down by virtue of their own weight.

Instead of forming each end of each tubular element with only two prongs or jaws, a greater number can be provided, as exemplified, for instance, in the arrangement of Fig. 5, where the tubular element 18 has each of its ends cut to form four longitudinally extending prongs 19, adapted to be bent and shaped to act as resilient segmento-spherical jaws similar to jaws 16, 16'.

Instead of being in the form of short tubular metallic sections, the elements may be in the form of solid bar sections of wood or plastic material, said sections being fitted at each end with one of the members of an articulated joint for connecting each element to an adjoining element. Such a construction is illustrated by way of example in Fig. 4, where the element is shown as consisting of a bar section 20, equipped at each end with a connecting member 21.

Said connecting member is shown in Fig. 6 before its prongs are shaped to form the resilient jaws of a spherical joint of the order of that illustrated in Figs. 2 and 3, the annular portion 22 of said member fitting over the end of the bar section 20. Four equidistant longitudinal prongs 23 extend outwardly from annular portion 22, and are subsequently bent and shaped to form four spring-acting segmento-spherical jaws such as shown at 23' in Fig. 4, adapted to embrace a ball, as explained in connection with the arrangement of Figs. 2 and 3.

Four additional longitudinal prongs 24 also extend inwardly from annular portion 22, said prongs having pointed ends 25 bent in to bite into the body of the bar section when the two parts are assembled, as shown in Fig. 4.

It is also possible to form a spherical joint between two adjoining elements without inserting a ball therebetween, by shaping the prongs of adjoining ends of adjoining elements so that they form interengaging male and female members respectively of the joint. Such a construction is illustrated in Figs. 7 and 8, where the metallic tubular elements 26, 27, have their adjoining ends cut and shaped to form a spring-acting spherical casing or socket 28, and a spherical button member 29 respectively, constituting the

female and male member of the joint, said button member fitting snugly within the socket 28.

A spherical joint may also be provided between adjoining elements consisting of solid bar sections, by providing the ball and socket of the joint, respectively, with a pointed stem adapted to be forced endwise within the body of the section of the adjoining element. Such a joint is illustrated in Fig. 9 where it is seen that the ball 30 and the socket 31 of the joint are each provided with a pointed stem 32, 33, said stems being preferably formed with burrs or barbs 34 anchoring said stems in position.

Referring again to Fig. 1 it will be seen that the uppermost element of each chain-like unit is provided with a ring 35 for suspending the unit from the curtain rod 13. The ring may be attached to the upper end element of each unit in any suitable manner. For instance, in Fig. 10 I show an end element comprising a solid bar section 36, equipped with a ring 37, said ring having a pointed stem portion 38 adapted to be forced endwise within the body of said section. In Fig. 11 the element consists of a tubular section 39, and the ring 40 is secured to the end of said section by bending the edge 41 of the section inwardly to engage the annular groove 42 formed in the body portion 43 of the ring.

The elements of a unit can also be articulately connected to one another by means other than a spherical joint. For instance, in Fig. 12 I illustrate a tubular element 44, connected to adjoining elements 45, 46, by means of a pivotal joint.

Each end of each element is cut to form two diametrically opposite prongs which, when bent inwardly and then in a longitudinal direction, will form lugs 47, adapted to register with the lugs 48 of an adjoining element, said lugs being pivotally connected by means of a rivet or eyelet such as shown at 49. Since eyelets can be easily secured in position by means of manually operated eyeletting tools, the elements can be readily connected to one another to form a unit without requiring the use of special machines or equipment.

In Figs. 13 and 14 I illustrate still another method of connecting the elements composing a unit to one another. In said Figs. 13 and 14, 50 designates elements in the form of flat bar sections provided at each end with an opening 51, 52. Said sections are connected to one another by means of spring links 53 insertable within openings 51, 52, as shown.

A screen built in accordance with my invention can be easily and quickly assembled; it can also be quickly altered to change its dimensions or design without involving the expenditure of unnecessary labor. Furthermore, its unitary construction makes it possible to employ a practically unlimited variety of materials, affording in their turn the possibility of achieving novel and attractive decorative effects, heretofore attainable only with great difficulty. The unitary construction is especially advantageous for the purpose of testing different decorative schemes and motifs, since the elements can be assembled and disassembled with the greatest ease, saving the artist or decorator much valuable time.

The constructional details of my invention may vary from those shown without departing from the inventive idea; the drawings should, therefore, be understood as being intended for illustrative purposes only, and not in a limiting sense.

I, accordingly reserve the right to carry my invention into practice in all those ways and manners which may enter, fairly, into the scope of the appended claims.

I claim:

1. A screen comprising a plurality of adjoining flexible units adapted to be attached at their upper end and to hang loosely therefrom, each unit being composed of a plurality of tubular elements connected end to end to one another to form a chain-like structure, each element having at one end the male member of a spherical joint and at the other end a cluster of spring acting prongs bent to form the female member of a corresponding spherical joint, adapted to engage the male member of the adjoining end of an adjoining element.

2. A screen comprising a plurality of adjoining flexible units adapted to be attached at their upper end and to hang loosely therefrom, each unit being composed of a plurality of elements

connected end to end to one another to form a chain-like structure, each element having at one end the male member of a spherical joint and at the other end a cluster of spring acting prongs bent to form the female member of a corresponding spherical joint, adapted to engage the male member of the adjoining end of an adjoining element.

3. A screen comprising a plurality of adjoining flexible units adapted to be attached at their upper end and to hang loosely therefrom, each unit being composed of a plurality of elements connected end to end to one another to form a chain-like structure, at least one end of each element having a cluster of spring acting prongs bent to form the female member of a spherical joint, and means associated with the adjoining end of an adjoining element, completing the spherical joint therewith.

MICHAEL RODELLI.
